METER INSERT FOR HEATERS

Filed Aug. 12, 1920

Inventor:
Gustav A. H. Binz.
By J. Stelle, Jr.,
Attorney.

UNITED STATES PATENT OFFICE.

GUSTAV A. H. BINZ, OF NEWARK, NEW JERSEY, ASSIGNOR TO YARNALL-WARING COMPANY, OF PHILADELPHIA, PENNSYLVANIA, A CORPORATION OF PENNSYLVANIA.

METER INSERT FOR HEATERS.

Application filed August 12, 1920. Serial No. 402,988.

My invention relates to a weir section, capable of being built into an open feed water heater construction without disturbing the water storage portion of the bottom 5 of the heater.

The purpose of my invention is to provide an intermediate section, containing a weir meter, and capable of insertion in existing heaters, supplying a meter compartment 10 therefor, and using the bottom of the heater for a catch basin or capable of being built 15 into a heater in a new construction.

A further purpose is to provide a weir meter section, capable of interfitting with 15 steel plate heater construction.

A further purpose is to provide a weir meter section, whose upper part is adapted 20 to act as the bottom of an open feed water heater, providing valved inlet between the feed water heater bottom water storage space 25 and the meter above the weir.

A further purpose is to form an entire 25 meter section with water storage for the heater and valve for water control, capable 30 of interconnection with the upper or upper and lower sections of a feed water heater.

Further purposes will appear in the specification and in the claims.

I have preferred to illustrate my invention 30 by but one general construction, among the various forms which it may take, showing a type which is practical, efficient and flexible, easily constructed and readily interchangeable for different feed water heater constructions, and which at the same time 35 well illustrates the principles of my invention.

In the drawing, Figure 1 shows a vertical, 40 longitudinal section, partly in side elevation, of this preferred form of my invention.

Figure 2 is a transverse section taken above the weir and partly in top plan, showing this preferred form.

Figure 3 is a transverse section, similar to 45 Figure 2, but showing a modified form of weir chamber.

Figure 4 is a section taken on the line 4-4 of Fig. 2.

In the drawing similar numerals indicate 50 like parts.

Many existing open feed water heaters cannot utilize weir meters because of the limited floor area available. If a weir meter can be interposed between existing 55 parts of this heater or beneath it, using a

portion of the heater structure, there is the double benefit of conserving floor space and saving in reduced installation cost and in time of installation. Even where the existing parts of the feed water heater cannot 60 be used, a new heater and meter can be built upon the same floor space as had been used for the heater above.

For new installations, even where ample 65 space is available, or where the location of other apparatus makes the installation of a weir meter between the heater and the feed pump difficult or undesirable, it is quite advantageous to be able to include a full 70 meter construction upon the ground space required by the heater alone, and without 75 losing any of the advantage of separate and distinct weir meter construction.

I have sought to provide an equipment of 75 this character with distinct and separate inlets, capable of control by the overflow of water in the catch basin, and which can be connected to the upper portion of an existing 80 feed water heater of some of the types already on the market, so that its upper section containing the inlet valve will form the bottom of the feed water heater and hold 85 part of the storage water of the heater.

By way of illustration and not by way of 90 limitation, I will now describe my preferred 85 form.

The feed water heater 4 is provided with the usual return steam connection 5 valved at 6 and with a make-up water connection 7, controlled by float 8, lever 9, rod 10, lever 11 and valve 12. There is also an overflow 95 control for water from the heater by means of a pipe 13, valve 14, a float 15, rock shaft 16 and operating rod 17, permitting water to flow out of pipe 13 when the valve is open.

The upper half of the heater is shown as joined to a meter section 18 and for that purpose terminating in flanges 18' which may be below or above the intended lower 100 level of storage water in the heater, but are here shown as below that level to provide for part of the storage within the section of heater above said flanges 18'.

The meter section 18, which here forms 105 an insert between old heater parts, is shown as flanged at 18' to cooperate with the flanges 18', and contains the combined floor and cover wall 19 providing a compartment 20 in the upper part thereof, which may form part 110

or all of the storage space for the heater and from which there is fluid connection through an outlet opening 21 and valve 22 with the meter section 18 above the weir. The combined floor and cover wall 19 forms a partition between the meter and heater chambers when the parts have been united. Water flowing out of the compartment 20 through said valve 22 will enter the meter space 23 above the weir through any desirable grating 24 or protected by any suitable baffle construction, so as not to disturb the flow of water or ruffle the level of water in the meter.

The difference between the sections shown in Fig. 2 and Fig. 3 lie chiefly in the fact that the inlet and weir in Fig. 2 are formed at 25 and 26 respectively, at diagonal corners of the construction, generally as shown in patent to L. G. Chase, No. 1,508,677, for diagonal flow meters, whereas in Fig. 3 the weir inlet (beneath the heater outlet 21) is at any suitable point along the side 27, preferably near the corner, and the weir shown at 26' is located at a point, approximately in the middle of one of the sides and not in or near a corner as in the construction of Figures 1 and 2.

The lower part of the weir section is flanged at 28 to cooperate with flanges 28' upon a lower section 29 which is intended to act as a storage basin and from which the outlet water flows to the pump through pipe 30.

Both the inlet water above the weir and the outlet through this pipe 31 can be controlled from a float or floats in the catch basin if desired, as these control connections are old in themselves. I have not explained them in any great detail herein but would refer to U. S. patent to Yarnall, No. 1,064,806, issued June 17, 1913, for any further information desired. In the illustration of this present application a control float 31 operates through rocker arm 32 and connections 33, 34, 35 to open and close valve 22 or keep it open to varying extents in inverse proportion to the height of water in the storage space.

The meter section is connected above the weir with a float chamber 36 containing a recording float 37, and carries a recorder case 38 and suitable recording mechanism, by which the rate of flow may be shown as in existing weir meter types.

A weir plate is shown at 39. At any convenient point sight openings are provided at 40 and valve controlled, pressure interchange connection between the weir chamber and the heater is provided by pipe 41.

The overflow of water from the weir passes down through an opening 42 into the catch basin, which is shown as of the extra storage type, i. e., permitting storage of water directly beneath the weir chamber.

This basin is formed by the lower half of

the standard feed water heater with its full filtering area and water storage capacity remaining undiminished. In the case of an existing heater this bottom section need not be moved and its connections remain undisturbed.

My meter insert offers considerable advantage, both in new and old installations. In the design of new heater-meter units, the manufacturer of rectangular heaters need not alter his heater patterns but can make the heater of square plates on the four sides as in the Swarthout heater, for example, and can insert the meter section between the standard upper and lower heater sections.

In the case of existing heater installation, the lower heater section originally used for water storage for the pumps remains undisturbed, but becomes the catch basin; the filter is left in place, and the float originally used for operating the make-up water valve is used for control of the float of the weir chamber. The upper heater section is raised and the meter insert is placed between the two heater sections. The placing of the desired floats or the changes in their connections involve little difficulty.

The heater is provided with a storage space wholly or largely provided by the compartment forming the upper part of the meter insert. However, this need not hold nearly the quantity of water desired as storage for the pump but only sufficient to "smooth out" or equalize the flow to the meter.

In view of my disclosure herein a variety of ways will occur to others skilled in the art by which advantage of my invention may be taken, suiting to the preference or whim of the designer. I aim to protect all of these forms which come within the spirit and scope of the invention.

Having thus described my invention, what I claim as new and desire to secure by Letters Patent is:—

1. A weir meter insert comprising a weir plate, a storage section above and in communication with the weir plate and of which the plate forms a part, a space below the weir for fall of liquid to a catch basin, a catch basin, a partition over the weir storage section and space and an open-top water storage section having the partition for its floor and adapted to be connected as the bottom of an open feed water heater.

2. A weir meter insert comprising a weir plate, a storage section above the weir plate and of which the plate forms a part, a space below the weir, for flow of water to a catch basin, a catch basin, a partition over the storage section and space, an open-top water storage section above the weir section for which the partition comprises the floor and separated upper and lower sections of an

open feed water heater, the open-top water storage section above the weir section completing the bottom of the feed water heater and the lower section of the feed water heater forming the catch basin for the falling water.

3. In a weir meter insert for the bottom of a feed water heater, a partition and walls at the top of the insert forming an upwardly facing open top water storage section, a weir and walls forming with it a storage compartment above the weir and below the partition and a valve-controlled, fluid-flow connection between the water storage section and the meter section above the weir.

4. A weir meter insert adapted for combination with an open feed water heater and comprising a weir compartment containing a weir, and an upper compartment, the floor of the upper compartment forming a cover for the weir compartment, adapted to form a portion of the water storage space of the feed water heater, and having an outlet opening, and a valve and connections to control the flow of water from this compartment to the weir chamber.

5. A weir insert having in the upper part thereof a water storage section and beneath it, a weir, a section including the weir, and valve-controlled fluid connection between the storage section and the body of the weir section above the weir in combination with a catch basin section, a float in said basin and connections therefrom to operate the valve.

35. 6. A heater and meter, comprising a feed water heater section lacking a bottom, in combination with a section containing a weir and storage compartment above the weir, the partition between them comprising the bottom of the feed water heater which forms a cover to the weir storage section, and valve-controlled discharge connections from the heater bottom to the weir chamber.

45. 7. A heater and meter comprising a feed water heater section open at the bottom, a weir chamber section having an upper compartment registering with the heater space and forming a part of the storage space for water in the heater, a valve and connections

between the bottom of the said upper compartment and the weir chamber, a catch basin section beneath the weir chamber section, and float-controlled connection from the catch basin to the valve, to control the flow to the weir chamber.

55. 8. A heater and meter, comprising a feed water heater section open at the bottom, a weir section, having an upper compartment registering with the feed water heater section and adapted to receive a part of the storage water of the heater and a valve and connections between the heater section and the weir section, the sections being generally rectangular in horizontal cross section, the meter section having a weir plate arranged diagonally across one corner thereof and a catch basin section beneath the weir section the basin whereof opens into the corner space of the meter sections cut off by the weir plate.

60. 9. A weir meter insert for the bottom of an open feed water heater, comprising a partition and walls forming a rectangular, upwardly facing, open top water storage section, a weir plate and walls forming a meter storage section above the weir and a valve-controlled fluid-flow connection between the first storage section and the meter section, the weir plate being located at one corner of the storage section above the weir and the water from the fluid-flow connection entering the meter at the diagonally opposite corner thereof.

75. 10. In a combined feed water heater and meter, the novelty which consists in utilizing the original bottom section of the feed water heater as a catch basin for the weir and interspersing between the upper section of the feed water heater and the lower section of the feed water heater walls forming a weir chamber whose weir discharges into the lower part of the feed water heater, a floor above the weir chamber, forming the bottom of the feed water heater and walls connecting the floor with the upper part of the feed water heater to form a storage space in the bottom of the feed water heater.
